(57) **CLAIM**

The ornamental design for a foldable tiltrotor aircraft, as shown and described.

DESCRIPTION

FIG. 1 is a top, right front perspective view of a foldable tiltrotor aircraft with the rotor nacelles facing forward; FIG. 2 is a front elevational view of FIG. 1; FIG. 3 is a right side elevational view of FIG. 1; FIG. 4 is a left side elevational view of FIG. 1; FIG. 5 is a top plan view of FIG. 1; FIG. 6 is a bottom plan view of FIG. 1; FIG. 7 is a top, right front perspective view of the foldable tiltrotor aircraft with the rotor nacelles facing upward; FIG. 8 is a front elevational view of FIG. 7; FIG. 10 is a left side elevational view of FIG. 7; FIG. 11 is a top plan view of FIG. 7; FIG. 12 is a bottom plan view of FIG. 7; FIG. 13 is a top, right front perspective view of the foldable tiltrotor aircraft in a folded position; FIG. 14 is a front elevational view of FIG. 13; FIG. 15 is a right side elevational view of FIG. 13; FIG. 16 is a left side elevational view of FIG. 13; FIG. 17 is a top plan view of FIG. 13; and, FIG. 18 is a bottom plan view of FIG. 13.

The broken lines in the drawings represent unclaimed environmental subject matter and form no part of the claim.
